UNITED STATES PATENT OFFICE.

CHARLES W. TRUSLOW, OF NEW YORK, N. Y.

RAILROAD-GATE.

SPECIFICATION forming part of Letters Patent No. 341,077, dated May 4, 1886.

Application filed January 23, 1886. Serial No. 189,464. (No model.)

To all whom it may concern:

Be it known that I, CHARLES W. TRUSLOW, of the city of New York, State of New York, have invented a new and useful Railroad-Gate, 5 of which the following is a specification.

My improved gate is designed to be used for similar purposes to the gates shown in Letters Patent No. 316,747, dated April 28, 1885, to D. W. Copeland, and No. 326,828, dated September 22, 1885, to W. C. Baird.

In the drawings I have shown the relative position of the various operative parts for different positions of the gate.

Figure 1 shows the gate entirely open. Fig. 15 2 shows the gate entirely closed. Fig. 3 shows the gate partially open. Figs. 4 and 5 show modifications.

In these drawings, which I am now about 20 to describe, I have shown what I at present believe to be the best form of apparatus for embodying my invention; but I do not limit myself to this form, since I am aware that many variations in form are possible without departing from the principle of my invention.

25 *a* and *b* are respectively upright posts arranged on opposite sides of the passage-way high enough to admit of a sufficient passage below the level of their tops.

c is a rod nearly as long as the post *b*, and 30 pivoted to the post at *d*.

e is a rod pivoted at one end to the free end of rod *c*, as at *f*. The rod *e* is nearly equal in length to the distance between the posts *a* and *b*, less the length of *c*, so that when the two rods 35 are horizontal in a line their combined length is sufficient to extend nearly from one post to the other.

g is a pulley, fixed to the post *b* above the free end of the rod *e* when upright. A chain, 40 *h*, is attached to the end of rod *e* or rod *c* at *f*, and, passing over the pulley *g*, is secured to the weight *i*, which is suspended by it.

j is a pulley attached to the post *a* near its top.

45 *k* is a chain passing over the pulley *j*, and attached at its respective ends to the movable pulley *l* and the weight *m*, which weight it suspends.

n is a chain passing over the pulley *l*, and 50 attached at its respective ends to rod *e* at *o* and to the drum *p*.

The size of the weights proper for produc-

ing the following described mode of operation will be readily understood.

The operation is as follows: While the parts 55 are in the position shown in Fig. 1, the weights will counterbalance the other parts, so as to retain them in position, and the gate will be kept open. When it is desired to close the gate, the attendant winds the chain *n* on the 60 drum *p*. The first result of so doing will be to cause the rod *e* to be drawn toward the post *a*, at the same time raising the weight *i* and moving the free end of rod *c* forward. The next result is to cause the pulley *l* to be drawn 65 downward, with a consequent raising of the weight *m*. When about half closed the parts will have reached about the relative position shown in Fig. 3. From this position to the closed position (shown in Fig. 2) the continued 70 winding of the chain *k* will cause the rod *c* to move forward and downward on its pivot *d* and the rod *e* to be lowered in a substantially horizontal position. When closed, the rods *c* and *e* will occupy a position end to end, extending substantially across the passage-way 75 at a height proper to prevent passing.

When it is desired to open the gate, the chain *n* is allowed to unwind, when the weights will cause the parts to resume the positions 80 shown in Fig. 1.

I have shown as by far the preferable mode of construction the two rods *c* and *e*; but these rods might be replaced by a continuation of the chain *n*, and in this case it would be desirable that the chain should not be secured to the end of chain *h*, but that it should pass around a movable pulley secured to the end of chain *h*, similarly to the movable pulley *l*; or the rod *e* may be retained and a chain substituted for the rod *c*. These modifications are shown in Figs. 4 and 5 of the drawings.

When it is desired to operate gates on opposite sides of a railroad-track, one gate may be operated, as shown, and the rope *n* from 95 the opposite side may be brought across under the track and wound on the drum *p*, so that both gates are operated simultaneously from the same drum.

Some of the advantages of the above-described gate may be stated as follows:

The amount of power required for operation is less than with other constructions.

The rods *c* and *e*, which I prefer in lieu of

a continuous chain, when used, afford more efficient obstruction to passers than would a chain, and at the same time sag less and can be made stronger for the same amount of weight.

5 The apparatus as a whole is distinguished by lightness, cheapness, and simplicity of construction.

For the purpose of still further supporting 10 the parts and preventing the gates from sagging, the post may be extended upward, as shown in post *a*, Fig. 1, and a pulley, *g*, placed at the top, over which passes a chain, *r*, having one end attached at *o* and the other to a 15 weight, *s*. The same arrangement may also be added to the post *b*, if desired.

I claim—

1. In combination, two posts, one arranged on each side of the passage-way, the drum *p*,

a connection, substantially as described, extending from the said drum to near the bottom of the opposite post and sustained by the chains *h* and *k*; which respectively depend from the upper portions of said posts, and are each provided with a counterpoise, substantially as 20 described.

2. In combination, the two posts *a* and *b*, the drum *p*, the connection *c*, substantially as described, secured at one end to the post *b* and at the other to the rod *e*, the chain *h*, supporting the two rods at their junction, the chain *n*, connected with the free end of rod *e*, and the movable pulley *l*, whereby the chain *n* is supported, substantially as described. 30

CHARLES W. TRUSLOW.
